[57] **CLAIM**

The ornamental design for an integral plastic carrying handle, as shown and described.

DESCRIPTION

FIG. 1 is a top and side perspective view of an integral plastic carrying handle showing my new design;

FIG. 2 is a sectional view thereof taken upon the line 2—2 of FIG. 3;

FIG. 3 is a bottom view thereof; and,

FIG. 4 is a side view thereof, the unshown opposite side being of identical appearance.
